US00D830537S

(12) **United States Design Patent** (10) **Patent No.:** **US D830,537 S**
(45) **Date of Patent:** **** Oct. 9, 2018**

(54) **WEARABLE DRUG DELIVERY DEVICE WITH ADHESIVE AND LINER**

(71) Applicant: **Becton, Dickinson and Company**, Franklin Lakes, NJ (US)

(72) Inventors: **Charles George Hwang**, Wellesley, MA (US); **John Prudden**, Manchester, MA (US); **Christopher Kovalchick**, Bedford, MA (US); **Russell Cole**, River Vale, NJ (US); **Andrew Allegretti**, Edgewater, NJ (US); **Jeffrey Reed**, Minden, NE (US); **Leya Colavito**, Ashby, MA (US); **Alessandro Pizzochero**, Chelmsford, MA (US); **J. Richard Gyory**, Sudbury, MA (US); **Justin Cumming**, Arlington, MA (US); **Kurt Maw**, Salem, MA (US)

(73) Assignee: **BECTON, DICKINSON AND COMPANY**, Franklin Lakes, NJ (US)

(**) Term: **15 Years**

(21) Appl. No.: **29/552,306**

(22) Filed: **Jan. 21, 2016**

(51) LOC (11) Cl. **24-02**

(52) U.S. Cl.

CLAIM

The ornamental design for a wearable drug delivery device with adhesive and liner, as shown and described.

DESCRIPTION

FIG. 1 is a top perspective view of a wearable drug delivery device with adhesive and liner showing our new design; FIG. 2 is a bottom perspective view thereof; FIG. 3 is a top plan view thereof; FIG. 4 is a left side elevational view thereof; FIG. 5 is a right side elevational view thereof; FIG. 6 is a front elevational view thereof; FIG. 7 is a rear elevational view thereof; and, FIG. 8 is a bottom plan view thereof. The broken lines show portions of the design that form no part of the claimed design.
